UNITED STATES PATENT OFFICE

JOHN LLOYD SCHUBERT, OF HILLSBORO, AND JOHNSTON EAKINS CALDWELL, OF MOUNT HAMILL, IOWA

ADJUSTABLE WRENCH

Application filed December 13, 1929. Serial No. 413,854.

The present invention relates to wrenches and has for its principal object to provide an adjustable wrench embodying a pivoted handle by means of which the jaws of the wrench may be moved into or out of cooperating positions with respect to the work.

A further object is to provide a wrench of a simple and practical construction, which is strong and durable, relatively inexpensive to manufacture and assemble and otherwise well adapted for the purposes for which the same is intended.

Other objects and advantages reside in the special construction, combination and arrangement of the various elements forming the invention as more fully hereinafter described and claimed, reference being had to the accompanying drawings forming part hereof, wherein like numerals refer to like parts throughout, and in which:

Figure 1 is a side elevational view with parts broken away and shown in section,

Figure 2 is a sectional view taken along a line 2—2 of Figure 1, and

Figure 3 is a similar view taken along a line 3—3 of Figure 1.

Referring now to the drawings in detail, the wrench includes a pair of cooperating jaws indicated at 5 and 6 respectively, the inner end of the jaw 5 being formed integral with a plate 7 having a cylindrical guide 8 formed along its edge adjacent to the jaw and extending outwardly at right angles from the jaw face.

The inner edge of the jaw 6 is provided with a pair of spaced parallel plates 9 adapted for positioning at opposite sides of the plate 7 and having a cylindrical recess 10 for slidably receiving the cylindrical guide 8 of the jaw 5. The jaws are thus mounted for sliding movement into and out of engagement with respect to the work positioned between the opposed faces of the jaw.

The guide 8 is formed with a bore 10 within which an expansible coil spring 11 is fitted, the spring having one end attached to a pin 12 depending within the recess 10 from the plate 9 and the other end of the spring is attached to an adjusting screw 13 threaded in one end of the bore 10.

The spring accordingly operates to yieldably urge the jaws into cooperating position. The plates 9 are provided at their inner sides with rack bars 14, the teeth of which are engageable by a pair of gear segments 15 formed on the bifurcated upper end of a handle 16, the bifurcations being disposed at opposite sides of the plate 7.

The plate 7 is formed with a series of apertures 17 within which a pin 18 may be selectively positioned to provide a pivotal mounting for the handle. The lower edge of the plate 7 is also formed with teeth 19 with which a stop 20 slidably carried by the handle is engageable for securing the handle in a desired position after the jaw 6 has been moved into engagement with the work by the pivotal movement of the handle.

The stop 20 is manipulated by means of a finger grip 21 extending laterally from the stop outwardly through a slotted opening 22 formed in one edge of the handle.

It will be apparent from the foregoing that upon the movement of the handle in a proper direction that the gear segment 15 engaging the racks 14 of the plate 9 carried by the jaw 6 that said jaw will be moved in a direction toward the jaw 5 for gripping the sides of a nut or other object. After the work has thus been engaged, the stop 20 is then moved into position for engaging the teeth 19 and the handle is thus rigidly secured with respect to the jaws.

It is obvious that our invention is susceptible to various changes and modifications in construction without departing from the spirit of the invention or the scope of the appended claims, and we accordingly claim all such forms of the device to which we are entitled.

Having thus described our invention, what we claim as new is:

1. A wrench comprising a pair of jaws, a plate formed on one of the jaws, a pair of plates formed on the other of said jaws and positioned at opposite sides of said first named plate, a guide at one edge of said first named plate, said pair of plates having a recess for slidably receiving the guide, rack bars formed on said pair of plates, a handle

having a bifurcated end and gear segments carried by the bifurcations engaging the rack bars for moving the jaws into and out of engagement.

- 5 2. A wrench comprising a pair of jaws, a plate formed at the inner end of one of the jaws and extending outwardly at right angles with respect to the jaw face, a pair of spaced plates formed on the other of said 10 jaws and positioned at opposite sides of said first named plate, a cylindrical recess formed between said pair of plates, a tubular cylindrical guide formed at the upper edge of said first named plate and slidable in said recess, 15 a screw threaded in said guide, a pin carried by said pair of plates, a spring having its ends attached respectively to said screw and said pin for yieldably urging the jaws together, rack bars formed on said pair of 20 plates, a handle having a bifurcated end pivotally attached to said first named plate, gear segments formed on said bifurcations and engageable with the rack bars for moving the jaws into and out of engagement and 25 cooperating means carried by the first named plate and the handle for securing the handle against movement.

In testimony whereof we affix our signatures.

30 JOHN LLOYD SCHUBERT.
JOHNSTON EAKINS CALDWELL.
